UNITED STATES PATENT OFFICE.

MICHAEL J. TRACY, OF ST. LOUIS, MISSOURI.

COMMUNICATION DEVICE.

Application filed February 18, 1927. Serial No. 169,216.

My invention has relation to improvements in communication devices adapted for insertion into a partition or wall and consists in the novel features of construction 5 more fully set forth in the specification and pointed out in the claims.

The present invention is a modification of that shown in my Patent No. 1,562,811 dated November 24, 1925, and, as in the device of 10 said patent, is particularly applicable for insertion in partitions in jails or other institutions of confinement. However, instead of providing a special sound transmitting panel as is shown in the patent referred to, 15 I provide a plurality of interrupted passageways in the muntins separating the glass windows in the partition.

The principal object of the present improvements is to provide a sound transmitting device for the purpose of carrying on 20 conversation on the opposite sides of the partition, through which device it is impossible to transmit any substance whatever, whether it be tools that could be used in jail 25 delivery, narcotics or liquor; a further object of the invention is to provide a conversation device that is practically invisible, and one possessing further and other advantages better apparent from a detailed 30 description of the invention in connection with the accompanying drawings, in which:

Figure 1 represents a side elevation of a fragment of a partition embodying my improved conversation device; Fig. 2 is a horizontal cross-section taken on the line 2—2 of Fig. 1; Fig. 3 is an enlarged front view of one of the glass windows, the muntins in which the window is set being constructed in accordance with the principles of my invention; Fig. 4 is a vertical cross-section taken 40 on the line 4—4 of Fig. 3; Fig. 4^a is a vertical cross-section taken on the line 4^a, 4^a of Fig. 3; and Fig. 5 is a horizontal cross-section taken on the line 5—5 of Fig. 3.

Referring to the drawings, 1 represents a jail partition on one side of which is a booth 2 for the accommodation of visitors when engaged in conversation with a prisoner on the opposite side of said partition. 45 The partition 1 is constructed principally of tool-proof steel plate and has a plurality of openings 3 in which are fitted non-frangible glass panels 4, said panels being constructed of glass of such composition that it will resist fracture by ordinary instruments. The windows 3 in the present in-

stance are arranged within a frame 5 and are separated by the customary mullions 6 and muntins 7.

As shown in Figs. 4 and 5, the muntins 6 and mullions are built up of laminations consisting of tool-proof steel plates 8, 9, 10 and 11 in intimate relation, the plate 9 being narrower than 8 and 10 which are contiguous to it so as to provide recesses 12, 12 for receiving the glass panels 4, 4. In the present instance only the muntins 7 are capable of transmitting sound, although I do not wish to be understood as restricting myself to confining the transmission of sound to the 70 muntins, as the mullions can also be constructed to permit passage of sound therethrough.

I accomplish the transmission of sound 75 through the muntins by the provision of interrupted passageways, the plate 8 having a plurality of counterbores 13 extending into it about half way from one edge, said counterbores being in communication with openings 14 traversing the walls 15 between the 80 bores 13 and the inner surface 16 of the plate 8. Each of the openings 14 communicates with a hole 17 passing through the plate 9. Plate 10 has a slot 18 extending sufficiently along the length of said plate 10 85 to span all of the openings 17 in the plate 9. Plate 11 is provided with a plurality of counterbores 19 similar to those in the plate 8, but in staggered relation to the counterbores 13 in the plate 8. A passageway 20 traverses the wall 21 between each counterbore 19 and the inner surface 22 of plate 11, said passageway 20 communicating with the slot 18 in plate 10. In view of the staggered 90 relation between the counterbores 13 and counterbores 19, the passageways 17 and the passageways 20 will not be oppositely disposed, but will communicate with the slot 18 in staggered relation. Therefore, even 95 though both sets of passageways 17 and 20 communicate with the chamber formed by the slot 18, such communication will not be in a direct line and it will be practically impossible for any substance whatever to be introduced through either passageway 13 or 100 passageway 19 and find entry into the opposite passageway.

Having described my invention, I claim:

1. A partition composed principally of tool-proof steel plate, a plurality of window panels therein, steel muntins separating said panels, and means embodied in said muntins 110

for transmitting sound therethrough, said means being arranged to obstruct the passage of any substance through the muntin.

2. A partition comprising a window panel, 5 and steel muntins encasing said panel, one of said muntins having tortuous passageways extending through it.

3. A partition comprising a window panel, a suitable frame enclosing said panel, said 10 frame being composed of laminations of sheet metal, said laminations having commu-

nicating passageways collectively forming a tortuous passage through the partition.

4. A partition comprising a window panel, a suitable frame enclosing said panel, said 15 frame having a chamber within it and passageways leading from opposite sides to said chamber, said passageways being disposed in non-aligning relation.

In testimony whereof I hereunto affix my 20 signature.

MICHAEL J. TRACY.
